STUART DEAN, OF INDIANAPOLIS, INDIANA, ASSIGNOR TO DEAN BROTHERS COMPANY, OF INDIANAPOLIS, INDIANA, A CORPORATION

STRAIGHT-LINE MECHANISM

Application filed July 1, 1927. Serial No. 202,894.

This invention relates to a power head for pumps.

The chief object of this invention is to secure substantially straight line movement of one or more piston rods thru a system of rocking parts without the use of a linear guide or guides for a piston rod or rods.

The chief feature of the invention consists in the provision of a lever arm which is pivotally and slidably mounted and so actuated that its pivotal and sliding movement at the actuated portion is confined to a substantially straight line movement.

The full nature of the invention will be understood from the accompanying drawings and the following description and claim.

In the drawings Fig. 1 is a perspective view and substantially a side elevation of a power head for pumps, illustrating the parts in the uppermost position. Fig. 2 is a similar view of the main portion of the invention showing the parts thereof in the lower-most or diametrically opposite position. Fig. 3 is a perspective view of the head and substantially an end view thereof. Fig. 4 is a top plan view. Fig. 5 is a view similar to Figs. 1 and 2 with the parts shown in one of the intermediate or neutral positions. Fig. 6 is a view similar to Fig. 2 showing a modified form of the invention wherein the link-confining member is replaced by an arcuate cam and groove. Fig. 7 is a view similar to Fig. 6 and a reverse form of the modified form. Fig. 8 is a view similar to Figs. 5 to 7 inclusive and of a modified form of the invention.

In the drawings 10 indicates a base extending upwardly from which are a plurality of uprights 11 which support in superposed relation a frame member 12. Mounted upon the base 10 is a pump head or valve chest 13 having the discharge line 14 and secured to said base by the anchoring bolts 15. Supported by the chest are the heads 16 and 17, extending upwardly from which are the cylinders 18 and 19 respectively in which are mounted pistons not shown carried by the piston rods 20 and 21 respectively.

The frame 12 includes a pair of spaced depending ears 22 which pivotally support a fulcrum pin or shaft 23 which is apertured

as at 24 to slidably support the extension 25 of a goose-neck shaped lever 26. The opposite end of the lever 26 is bifurcated as at 27 and each bifurcation extends into a cup 28 adjustably secured at 29 to the end of one of the piston rods. The cup 28 is deeply recessed and is adapted to contain hard grease for lubrication of the pin and arm connection, the pin being indicated by the numeral 30. The pins 30 of the bifurcated arm 27 of the goose-neck lever 26 have a substantial straight line and parallel movement as indicated by the dotted lines *a* and *b*.

The mechanism for causing the two pins 30 to have substantially parallel and straight line movement without the aid of straight line guides comprises a link 31 pivoted at 32 to the goose-neck lever 26 and pivotally supported by the fulcrum pin or shaft 33 mounted in a pair of ears 34 depending upon the frame 12. The centers of the fulcrum pin or shaft 23 and the pin or shaft 33 lie in a plane substantially parallel to the frame 12. The end of the link 31 is pivotally supported by shaft 33 and is substantially U-shaped and is positioned angularly thereof as at 35. This prevents said link from having any other movement except pivotal movement about the axis 33. The pivot 32 between the link 31 and the goose-neck 26, has an arcuate path as indicated by the dotted line 36. As the goose-neck lever is tilted on its pivot 23, the tilting movement or deviation from the straight line by reason of the arcuate movement thereof is compensated for by the restraint imposed by the link 31 which travels an opposing arcuate path, the two paths being equal in effect so that the bifurcated end 27 rises and descends in a substantially straight line. To secure such straight line movement, the goose-neck moves in and out by reason of the slide support of the extension 25 thereof in the aperture 24 of the pin or shaft 23, and such in or out movement is substantially equivalent to what would occur if the aforesaid mechanism were not provided or the goose-neck deviated from the tangent to the arc about the fulcrum 23 at the intersection with the center plane.

The means for tilting the goose-neck lever

upon its fulcrum comprises a power shaft 40 suitably actuated, which may be by motor or otherwise, and mounting gear 41, said shaft being rotatably supported in the bearings 42 in the frame 12. Pinion 41 meshes with gear 43 mounted on the projecting end of shaft 44 rotatably mounted in a U-shape extension 45 of the main frame 12, thus forming a multiple out-board bearing for said shaft. 5

10 The gear 43 has rigidly mounted thereon an eccentric or crank pin 46 which actuates a cross-head member having a crank or eccentric pin mounting portion 47 and a slidably mounted portion 48 having an opening 49 extending therethru and substantially transverse to the pin opening and receiving a guide member 50 which slidably supports the cross-head whereby rotational movement of the gear is transmitted into oscillatory movement of 15 the lever. The rod 50 is suitably secured in bearings or ears 51 and 52 of the gooseneck shaped lever 26 and the reduced end 25 thereof extends as aforesaid thru the apertured fulcrum 23. As the pinion is rotated, the eccentric pin 46 is slowly revolved which reciprocates the combination crank arm and power head which, by sliding to and fro on the guide rod 50, causes rising and lowering movement 20 of the goose-neck lever 26 about the pivot 23. 25

30 However, such arcuate movement is modified by the link 31 which causes said goose-neck to slide to and fro upon or in the fulcrum support 23 in amount substantially equivalent to the arcuate deviation from the tangent. Thus 35 the end of the lever 26 is caused to have substantially straight line movement, and thus straight line movement is obtained without the necessity of providing a straight line guide.

40 In Fig. 6 a modified form of the invention is illustrated and like parts bear like numerals and similar parts bear numerals of the one hundred series. The frame 112 has the extension 22 rotatably supporting the pivot 23 which rotatably supports at 24 the reduced extension 25 of the goose-neck lever 126. 45 The goose-neck lever is rocked upon its pivot by the eccentric 46 rotating in strap 47 integral with the cross head 48 slidably mounted 50 on the guide 50. Thus as the crank pin 46 is rotated with and by gear 43 the cross head 48 raises and lowers lever 126 and said lever moves in and out on its slide support 24 and pivot 23 and the sliding movement is confined 55 by means of a pin 133 supported in an extension 134 of the frame 112. The lever 126 has an enlarged portion 135 provided with an arcuate slide 132 which receives pin 133 and thus the attempt of lever 126 to deviate from 60 the before-mentioned tangent plane is compensated by the shape of the slot 132 and the sliding movement of the lever occasioned by the fixed position of pin 133 in said slot. 65

In Fig. 7 the same result is obtained, that is, straight line motion, but in this form of

the invention, a reverse construction is illustrated, like parts being provided with like numerals and similar parts of the same numerals of two hundred series. The goose neck 226 is pivotally supported on the frame 212 having the ear 22 supporting the pivot 23. In this form of the invention the pin 233 is carried by the goose neck and said pin rises and falls in the arcuate slot 232 formed in the extension 234 of the frame 212. The tendency of the goose neck lever 226 to depart from the tangent plane in the tilting thereof is prevented by the goose neck being slid to and fro an amount equal to said tendency so that straight line movement of the end of 70 the lever obtains. 75

In Fig. 8 a modified form of the invention is illustrated, the modification being two-fold. Gooseneck lever 326 has a crank and rod connection with pin 346 or gear 43. This eliminates the cross head construction and in large sizes the elimination of this friction is a considerable gain in efficiency. Also instead of the sliding bearing extension, the ear 322 of frame 312 pivotally supports at 323 the link 324 pivotally supporting pin 325 rigid with extension 350 of the gooseneck. 80 85

The invention claimed is:

In a mechanism of the character described the combination of a lever having a goose-neck extension at one end and pivotally and slidably supported at its opposite end and including a cross-head confining guide support intermediate the pivotal support and the opposite end of the lever, and a confining link stationarily pivoted at one end and pivoted to the lever at the opposite end adjacent the cross-head support and securing substantially linear reciprocation of the goose-neck extension of the lever. 90 95

In witness whereof, I have hereunto affixed my signature.

STUART DEAN.
